UNITED STATES PATENT OFFICE.

EDGAR C. LITCHFIELD AND DUDLEY GARST, OF WATERLOO, IOWA, ASSIGNEES TO THE LITCHFIELD MANUFACTURING COMPANY, OF WATERLOO, IOWA.

MANURE-SPREADER.

13,047.

Specification of Reissued Letters Patent. Reissued Nov. 30, 1909.

Original No. 872,000, dated November 26, 1907, Serial No. 321,169. Application for reissue filed April 15, 1908. Serial No. 427,285.

To all whom it may concern:

Be it known that we, EDGAR C. LITCHFIELD and DUDLEY GARST, citizens of the United States of America, and residents of 5 Waterloo, Blackhawk county, Iowa, have invented certain new and useful Improvements in Manure-Spreaders, of which the following is a specification.

Our invention relates to improvements in 10 manure spreaders, and the object of our invention is to so modify the arrangement and respective lengths of the different teeth along the exterior cylindrical periphery of the beater drum as to effect a more complete 15 disintegration and delivery of masses of compacted manure than could be accomplished by the ordinary means. This object we have achieved by the means which are hereinafter described and claimed, and 20 which are illustrated in the accompanying drawings, in which—

Figure 1 is a side elevation of the rear of a spreader box and beater drum, the forward end of said box being represented as 25 being broken away; and Fig. 2 is a plan view of the same.

Similar characters of reference refer to similar parts throughout both views.

Cow manure, which has become mixed 30 and compacted with straw or tough wire grass, forms into large dense masses which are difficult to disintegrate and distribute evenly by means of a beater drum having teeth of an equal length. Such teeth either 35 slide over such masses, or else discharge the lumps without proper disintegration. We have varied the arrangement and length of the beater teeth, in order to accomplish more efficiently the operations of breaking 40 apart such dense compactions, as follows.

A beater drum *f* may have its journals, *e*, *e*, rotatably mounted in brackets *d*, *d*, the latter extending from the rear end of the spreader box *a*, or otherwise as desired, and 45 said drum may be arranged to rotate near the rear end of a movable apron *c*, the latter moving over a roller *b*.

The drum-heads *f* may be connected by 50 separated longitudinal slats *i* or may be attached to the ends of a cylinder, if desired, but in either event, the teeth *g* and *h* are radially attached to the cylindrical periphery of the drum. We have shown the teeth graded into two lengths, of which the teeth 55 *h* are but one half the length of the teeth *g*,

and are alternately located in each row, the locations of the teeth on the several rows being such that while but few teeth are placed in any one row, one revolution of the drum will cause the separating space along the 60 periphery of said drum to be swept at equal close intervals. We do not, however, mean to limit ourselves to the exact arrangement of location or spacing apart of the teeth as shown, as the arrangement may be widely 65 varied in both particulars.

When a load composed of dense masses of compacted manure and straw or other tough binding material is carried toward and against the teeth of a beater drum like that 70 herein shown, the longer teeth dig into the lumps while such lumps tend to push in upon the shorter teeth, and are thus spurred and agitated until completely disintegrated and delivered. The effect is to greatly 75 reduce the peripheral friction of the beater drum as also the draft of the machine, as the lumps of manure are segregated and broken apart separately, instead of bearing upon said drum in a solid mass as is the case when 80 the teeth of the beater drum are of even length.

The teeth may be formed of more than two lengths or sizes if desired, as the principle involved in our invention is the use of varying lengths to effect a varied agitation and stirring of compacted masses, and a breaking up of the solid wall of material before the drum by separating its component lumps 85 from each other to be separately disintegrated. 90

Having described our invention, what we claim as new and desire to secure by Letters Patent, is:—

1. In a manure spreader, the combination 95 with means for positively moving the mass to be spread to the discharge point, of a beater drum located closely adjacent to the discharge end of said means, said drum provided with a plurality of series of disintegrating and distributing teeth of varying 100 lengths, teeth of each series being distributed at intervals across the entire width of the drum.

2. In a manure spreader, the combination 105 with means for positively moving the mass to be spread to the discharge point, of a beater drum located closely adjacent to the discharge end of said means, said drum provided with a plurality of series of disint- 110

tegrating and distributing teeth, the teeth of each series differing in length from the teeth of the other series, teeth of each series being distributed at intervals around and 5 along the entire circumferential surface of the drum.

3. In a manure spreader, the combination with a movable apron for conveying the mass, of a beater drum located adjacent to 10 the discharge end of said apron, said drum provided with a plurality of series of disintegrating and distributing teeth, the teeth of one series varying in length from that of the other series, teeth of each series being 15 distributed at intervals around and along the entire circumferential surface of the drum, and the teeth of one series alternating with the teeth of another series.

4. In a manure spreader, a rotating beater 20 drum, a plurality of series of disintegrating and distributing teeth carried by said drum, the teeth of each series differing in length from the teeth of the other series, teeth of each series being distributed along and 25 about the entire circumferential surface of the drum, and the teeth of each series being intermingled with the teeth of the other series.

5. In a manure spreader, a rotating beater

drum provided with a plurality of series of 30 disintegrating and distributing pin teeth located and intermingled over the entire cylindrical surface, the teeth of each series differing in length from the remaining teeth.

6. In a manure spreader, the combination 35 of a movable apron, a beater-drum rotatably supported at one end thereof, and long and short distributing teeth alternately and spirally arranged upon the exterior periphery of said beater-drum.

7. In a manure spreader, the combination with means for moving the mass to be spread to the discharge point, of a beater drum located at said discharge point, said drum having distributed and intermingled along 45 and about its peripheral surface a plurality of series of teeth of varying lengths, the arrangement being such that the number of paths described by the teeth upon rotation of the drum is greater than the number of 50 such teeth lying upon one side of the axis of rotation in any plane containing the axis of rotation.
